(57) **CLAIM**

The ornamental design for a vehicle steering wheel as shown and described.

DESCRIPTION

FIG. 1 is a front view of a vehicle steering wheel according to the new design;

FIG. 2 is a bottom view thereof;

FIG. 3 is a rear view thereof;

FIG. 4 is a top, rear, right side perspective view thereof;

FIG. 5 is a left side view thereof;

FIG. 6 is a right side view thereof; and,

FIG. 7 is a top view thereof.

The broken lines illustrate portions of the vehicle steering wheel that form no part of the claimed design.
